UNITED STATES PATENT OFFICE.

JAMES F. MIRRIELES, OF CINCINNATI, OHIO, ASSIGNOR TO THE PRECISION TRUING MACHINE AND TOOL COMPANY, OF CINCINNATI, OHIO, A CORPORATION OF OHIO.

MECHANISM FOR TRUING AND DRESSING GRINDING WHEELS.

Application filed March 5, 1923. Serial No. 622,888.

To all whom it may concern:

Be it known that I, JAMES F. MIRRIELES, a citizen of the United States, residing at Cincinnati, in the county of Hamilton and State of Ohio, have invented certain new and useful Improvements in Mechanism for Truing and Dressing Grinding Wheels, of which the following is a specification.

My invention is an elaboration on the inventions shown, described and claimed in Letters Patent Nos. 1,395,391, 1,395,392, 1,395,393 and 1,395,394, for devices or mechanism for truing and dressing grinding wheels, dated November 1, 1921, and granted on the applications of Edward R. Conners, and upon applications for Letters Patent by said Conners, for improvements in mechanism for truing and dressing grinding wheels, Serial Nos. 510,727 and 510,728, filed October 27, 1921.

My invention relates to mechanism for truing and dressing grinding wheels, such as emery wheels employed in machinery for grinding or polishing the surfaces of metal in precision grinding, and is employable for truing and dressing the grinding wheel without removing the grinding wheel from the grinding or polishing machine.

It is the object of my invention to provide a rotary abrading part arranged to contact the grinding surface of a grinding wheel in such manner as to cause rotation to be imparted to the rotary abrading part by the rotating grinding wheel, and means whereby the speed of rotation of the rotary abrading part is retarded with relation to the speed of rotation of the rotary grinding wheel in order to control the fineness of grinding surface of the grinding wheel being treated; further, to provide novel means whereby the rotation of the rotary abrading part is resisted; further, to provide novel means for mounting the rotary abrading part; and, further, to provide novel resilient means whereby to maintain the mandrel on which the rotary abrading part is mounted in its true path of movement; further, to provide novel braking means for the rotary abrading part; and, further, to provide novel means for adjustably securing the rotary abrading part in position in the machine.

The invention will be further readily understood from the following description

and claims, and from the drawings, in which latter:

Fig. 1 is a plan view of my improved device applied to an exemplified grinding machine, partly broken away.

Fig. 2 is a cross-section of the same taken on the line 2—2 of Fig. 1, and partly broken away.

Fig. 3 is a side elevation of my improved abrading device.

Fig. 4 is an axial section of the same taken on the line 4—4 of Fig. 3.

Fig. 5 is an axial section of the same, partly broken away, and taken in the plane of the line 5—5 of Fig. 4.

Fig. 6 is a detail in cross-section, taken in the plane of the line 6—6 of Fig. 4.

Fig. 7 is a side elevation of my improved device, partly broken away, and shown in connection with a sectional detail of the machine on which it is mounted, taken in the plane of the line 2—2 of Fig. 1; and,

Fig. 8 is an axial section of the same, taken in the plane of the line 8—8 of Fig. 7.

I have exemplified my invention as employed in connection with a so-called grinding or polishing machine employing a rotary grinding wheel 11 for effecting the grinding or polishing.

The work to be ground or polished, which may for instance be a shaft, is arranged to be placed between suitable centers 12, 13, of which 12 may exemplify a head center, arranged to be rotated by a suitable driving means, as a pulley 14, the usual quill 15 in which the head center is supported in usual manner being journaled in a bearing 16, of a head-stock 17, slideable laterally on guideways 18, 19, of a table 20.

The tail-center 13 is mounted in a suitable sleeve 21, movable axially in a bearing 22, in usual manner, the bearing being on a tail-stock 23 laterally adjustable on the guideways 18, 19, of the table 20.

The table is exemplified as pivotally mounted by a pivot 25 on a saddle 26, which has lateral reciprocating motion imparted thereto by power means, in usual manner, as by means of a pinion 27, suitably driven, meshing with a rack 28 extending lengthwise of the saddle. The saddle is slideable laterally on guideways 29, 30, on the frame 31 of the machine.

The grinding wheel 11 is suitably fixed

to a shaft 34 journaled in bearings 35 of a slide 36, adjustable toward and from the work-table on guideways 37, by any suitable means, the slide being arranged to be 5 clamped by means of suitable T-bolts and nuts 38, the heads of the T-bolts coacting with the T-slot 39 in the frame, and the nuts clamping the slide to the frame. The shaft is rotatable in suitable manner, as by means 10 of a belt passing about suitable pulleys 40, 41, fixed to the shaft.

In the exemplification, the work located between the centers may be caused to reciprocate axially in planes parallel to the axis 15 of rotation of the shaft of the grinding wheel for grinding or polishing straight work, or the table may be adjusted to an angle with relation to said parallelism, effected, for instance, by the gauge 42, and rotation of the 20 handle 43.

I have in the present exemplification illustrated a reciprocating table on which to mount the work, the grinding wheel having a stationary position, although, as explained 25 in the aforesaid patents and applications, the relations of the parts may be reversed, the work being stationarily positioned and the grinding wheel having reciprocations imparted to it. I have instanced the abrad- 30 ing part as acting on the grinding wheel in the absence of work between the centers.

The rotary abrading part is exemplified as an abrading wheel 45. It is preferably of a texture much harder than the grinding 35 wheel and of much smaller diameter than the diameter of the grinding wheel on which it is to operate. The rotation imparted to the grinding wheel is instanced as in the direction of the arrow *a*, while the rotation 40 imparted to the abrading wheel through the medium of the grinding wheel is instanced as in the direction of the arrow *b*.

The grinding wheel during operation becomes impregnated with particles of dirt or 45 metal from the work being operated on, and becomes comparatively glossy and thereby loses its grinding effect, its granular structure also becoming dull at the grinding face, thereby reducing its grinding or polishing 50 properties. By means of my invention, the particles of dirt and metal are removed from the grinding surface of the grinding wheel and the recesses and pores in said grinding surface are cleared and the particles or 55 grains of the grinding wheel are sharpened.

The grinding or polishing effect of the grinding wheel is determined by the fineness or coarseness of its grinding surface, and I have provided means whereby to regulate 60 such fineness or coarseness in order to dress the grinding wheel according to the work which it is to perform.

I obtain a more marked cleaning and abrading effect of the abrading wheel upon 65 the grinding wheel by mounting the abrad-

ing wheel in such manner that its plane perpendicular to its axis of rotation is at an angle to the plane of the grinding wheel perpendicular to the axis of rotation of the latter. In this manner I obtain an additional swirling action upon the grinding wheel in order to clean the peripheral interstices or pores of the grinding wheel by brushing or drawing out the dirt or particles of metal which may be lodged in said interstices or pores. This angle may be instanced as one of fifteen degrees (see Figs. 1 and 2), although this is given as an illustration and not as a limitation.

I prefer also to mount the abrading wheel 80 on a shank located at the side of but close to the abrading wheel, and to adjust the shank axially and rotatively for adjusting the position of the abrading wheel with relation to the grinding wheel, and to so mount 85 the shank that its axis extended will be a chord, indicated by the dotted line *c*, to the circle of the grinding wheel intersecting the horizontal plane, indicated by the dotted line *d*, in which the axis of rotation of the 90 grinding is located, at a slight angle to said horizontal plane, instanced as six degrees with the point of intersection *e* located between the abrading wheel and the axis of rotation of the grinding wheel, and to locate 95 the contact point of the abrading wheel with the grinding wheel slightly above said horizontal plane.

The nearer the abrading wheel is adjusted 100 into parallelism with the grinding wheel the finer will be the finish imparted to the grinding wheel for producing polishing effects on the work, and the greater the angle to which the abrading wheel is adjusted with relation to the grinding wheel, preferably 105 not exceeding thirty degrees, the coarser will be the finish imparted to the grinding wheel for cutting effects upon the work, although I have found that an angular adjustment of substantially fifteen degrees 110 above-mentioned, the adjustment for coarseness or fineness being obtained by the braking mechanism hereinafter described, is advisable for a great range of work.

The abrading wheel is exemplified as secured to a mandrel 51, provided with a flange 52, and is shown clamped to said mandrel by means of a nut 53, a washer 54, for instance of leather, being located between the grinding wheel and the flange, 120 and washers 55, 56, the former of leather, being located between the abrading wheel and the nut, the nut clamping said abrading wheel and washers between the flange and the nut.

A bearing-housing 58 has bearings 59, 60, therein for the mandrel, the bearings being shown as combined radial and end-thrust ball-bearings. The ball-bearing 59 comprises an inner race 61 and an outer 130

race 62. The bearing 60 is shown as comprising an inner race 63 and an outer race 64. The outer races are exemplified as having raceways with single side walls presented toward each other and are shown fixed in the housing. Thus the race 61 is limited in endwise direction by an annular shoulder 66 in the housing received about the flange 52, and a tube 67 located between the outer races and forming a separating medium between the same. A nut 68 is threaded into the outer threaded end 69 of the housing, this nut being a ring-nut and having end-holes 70 for receiving a suitable wrench for turning the nut and clamping the outer races and the separating tube between the shoulder 66 and the nut.

The inner race 61 is received against the flange 52. A brake-member 73, shown as a wheel, is secured to the mandrel, being shown threaded to an intermediate threaded portion 74 of said mandrel. The brake-member is provided with holes 75 for receiving a suitable wrench. The screwing of the brake-member over the median threaded portion of the mandrel clamps the inner race 61 between it and the flange 52. The outer periphery of this brake-member is shown as an annular braking surface, with which a coacting brake-member, exemplified as a brake-shoe 76, is arranged to act.

A sleeve 81 is received about the reduced portion 82 of the arbor, and has lengthwise or axial movement thereon. The sleeve is shown provided with an annular flange 83 and a threaded end 84. The race 63 is received about the sleeve against said shoulder, a nut 85 being threaded over the threaded end of the sleeve and arranged for clamping the race 63 between said nut and the annular shoulder 83.

In order to cause combined rotation of the sleeve and the mandrel and permit lengthwise movement between the same, I show the mandrel as provided with a longitudinal slot 86 in which a pin 87 located in the sleeve is received. The nut is provided with suitable holes 88 for receiving a suitable wrench.

A spring 91, shown as a helical spring, is received about the end of the mandrel. The spring is arranged to exert relative axial force in opposite directions upon the mandrel, to which the race 61 is fixed, and the sleeve 81, to which the race 63 is fixed, instanced as an approaching force between said races for causing the balls between the races of the respective ball-bearings to be urged toward each other for causing intimate operative contact between said balls and the opposed side walls of the ways in the races, in order to take up wear and to normally cause continuous proper bearing relation in the ball-bearings, whereby vi-

brations and axial movements of the abrading wheel with relation to the bearing-housing are avoided, and accurate dressing action upon the guiding wheel is assured.

The spring is shown as a helical spring, the inner end of which bears against the outer end of the nut 85 and the outer end of which bears against an annular shoulder 92 of a nut 93 adjustable over the threaded end 94 of the mandrel. This nut is shown as provided with holes 95 for receiving a suitable wrench. Adjustment of the nut 93 adjusts the distance between the shoulder 92 which is adjustable on the mandrel and the sleeve 81, which is movable axially with relation to the mandrel, causing resilient approach in axial direction between the inner races of the respective ball-bearings, one of which is secured to said mandrel and the other of which is secured to said sleeve, in order to cause resilient approach between the balls of said ball-bearings in axial direction and proper bearing of said balls upon the opposed walls of the raceways in their respective races.

A closing cap 97 is received over the outer end of the bearing-housing, being shown as provided with a threaded stud 98 and an annular flange 99 screwed firmly against the outer end of said bearing-housing. The cap is provided with an inner socket 100 in which the outer end of the mandrel and the parts mounted thereon are received.

The threads of the threaded portions of the mandrel are preferably such as to be counter to the direction of rotation of the abrading wheel, and are instanced as right hand threads.

A shank 105 is provided for the bearing-housing, and is exemplified as having a taper end 106 received in a taper socket 107 of the bearing-housing, and is provided with a threaded end 108 received in a threaded socket 109 in the bearing-housing. The turning of the shank in said sockets rigidly connects the bearing-housing and the shank.

The shank is exemplified as having a bore 111, in which a stem 112 is received. The brake-shoe 76 has connection with the inner end of the stem, for controlling the braking action of the shoe upon the brake-wheel of the abrading mandrel. The inner end of the stem has lengthwise slidable movement in a bearing 113 at the inner end of the shank, and is provided with a socket 114 in which a pin 115 extending from the brake-shoe is received. This brake-shoe may be instanced as formed out of fiber, bakelite or other wear and heat resistant substance.

The stem is provided with a shoulder 116, exemplified as forming a reduced portion 117 of the stem, and the outer end of the bore is provided with a threaded portion 118. A nut 119 is adjustable in the threaded por-

tion and may be turned by a suitable wrench received in slots 120 in said nut. A spring 121 surrounds the stem between the nut and the shoulder. Adjustment of the nut regulates the tension of the spring and consequently the force of application of the brake-shoe to the coacting brake-member on the mandrel.

A quick-release device is provided for the 10 braking means, and is instanced as a handle 125, provided at the outer end of the stem, being shown pinned thereto by a pin 126. The handle is provided with lugs 127 received in slots 128 in the shank. The lugs 15 and slots are preferably of such length that considerable movement of the stem is permitted so as to accommodate for firm application of the brake-shoe upon the coacting brake-member and for wear of the brake-shoe.

The lugs are received in the slots when the 20 releasable braking member, instanced as the brake-shoe, is applied to its coacting brake-member, or the lugs may be arranged cross-wise of the slots and contact the outer end of the shank, for relieving the braking contact between the braking members, and releasing said releasable braking member from the pressure of the spring 121.

30 Adjustment of the spring 121 adjusts the force of application of the brake-shoe on its coacting brake-member, this resistance being communicated as a resistance to rotation of the abrading wheel at the meeting faces 35 between the abrading wheel and the grinding wheel which is being operated on. The greater this resistance the coarser will be the dressing effect upon the grinding wheel. When the brake-shoe is relieved from its 40 coacting brake-member, more ready rotation of the abrading wheel by means of the grinding wheel takes place, resulting in a finer dressing or finish being applied to the grinding wheel. Adjustment of the nut 119 adjusts the fineness or coarseness of resulting 45 action of the abrading wheel on the grinding wheel. Relief of braking action is obtained by means of operating the outer handle 125.

I have provided means for readily affixing 50 the abrading means to the grinding or polishing machine. The table of the grinding or polishing machine is in the present instance provided with a guide 131 and a rail 132. A clamp 133 is provided with a jaw 134 co-acting with the guide and a clamping 55 means comprising a jaw 136 having an inclined face 137 on the body of the clamp and a clamp-plate 138, the inclined face and the clamp-plate being arranged to clamp upon 60 the rail 132.

A stem 141 is located in a bearing 142 of the clamp and is held non-rotative therein by being provided with a groove 143, a pin 144 in the body of the clamp being received 65 in said groove. An adjusting nut 145 and

a lock-nut 146 are received over the threaded end 147 of said stem. The head 149 of said stem is shown as a flat head, a fork 150 of a handle 151 being received about said head and articulated therewith by means of a pin 70 152. The body of the clamp has a socket 153 in which there is a spring 154 surrounding said stem, normally exerting separating movement between the bottom of the socket and the clamp-plate 138.

75 A cap 156 is provided with a slot 157 through which the head of the stem is received. The inner end of the fork 150 is provided with cams 159 and shoulders 160, arranged to bear against said cap, and to cause clamping movement between said cap and the clamp-plate 138 at one side of the rail 132 and the inclined face 137 at the other side of said rail, causing clamping of the jaw 138 upon the rail 132. Rotation of the clamp-plate 138 on the stem is prevented by means of a pin 161 fixed in the body of the clamp and received in a hole 162 in said clamp-plate.

80 The body of the clamp is provided with a bearing 165, shown as a clamp-bearing, in which the shank 105 is received, and in which said shank may be adjusted axially and rotatively, for locating the periphery of the abrading wheel in correct relation to the periphery of the grinding wheel. When such adjustment has been made, the clamp bearing is clamped about the shank by means of the bolts 166, journaled in holes 167 of a cheek 168 and threaded in threaded holes 169 of a cheek 170, the cheeks being located at the respective sides of a split 171 in said clamp-bearing, which is thereby constituted a split-bearing. The bearing-housing 58 is 85 provided with a protective flange 175 for the 100 abrading wheel.

105 The bearing-housing is exemplified as an oil casing for inclosing a body of oil for oiling the ball-bearings and movable parts 110 within the housing. A felt washer 176 is clamped between the end of the housing and the washer 54 of the abrading wheel for preventing leakage of oil, the oil being further retained in said housing by means of the closing cap 97. A felt washer 177 filling the bore in the shank 105 and held against the shoulder 116 by means of a metal washer 178 clamped upon said felt washer by the spring 121, retains the oil in the shank. The oil may be supplied into the housing 120 through a hole 179 closed by a cap 180 and communicating with an oil groove 181 extending lengthwise throughout the outer periphery of the tube 67.

125 My improved device provides ready, economical and compact means for producing truing and dressing effects upon the grinding wheel, without removing the same from the grinding or polishing machine, provides ready means for adjusting the fineness or 130

coarseness of the grinding surface of the grinding wheel by means of the adjustment of inclination of the plane of the abrading wheel with relation to the plane of the 5 grinding wheel, provides ready means for adjusting the fineness or coarseness of the dressing effect of the abrading wheel, in any of its adjusted positions, by means of the braking means, and provides ready means 0 for quick release of the braking means.

Having thus fully described my invention, what I claim as new, and desire to secure by Letters Patent, is:

1. In mechanism for truing and dressing 5 grinding wheels, the combination of a normally quiescent rotary abrading part for coaction with a rotary grinding wheel, a support for said rotary abrading part comprising a shank, a table comprising a guide 10 and a rail, and a clamp comprising a bearing for said shank and clamping means, means for permitting adjustment of said shank in said bearing, said clamping means comprising a jaw for coaction with said 15 guide and a movable jaw, a spring normally retracting said movable jaw, and a handle comprising a cam for clamping said movable jaw to said rail.

2. In mechanism for truing and dressing 10 grinding wheels, the combination of a normally quiescent rotary abrading wheel, a support therefor comprising means for angular adjustment of the plane of said rotary abrading wheel with relation to the plane 15 of the grinding wheel, and braking means for said abrading wheel.

3. In mechanism for truing and dressing 10 grinding wheels, the combination of a normally quiescent rotary abrading wheel, a support therefor comprising means for angular adjustment of the plane of said rotary abrading wheel with relation to the plane of the grinding wheel, braking means for said abrading wheel, and adjusting 5 means for controlling the braking effect of said braking means.

4. In mechanism for truing and dressing 10 grinding wheels, the combination of a normally quiescent rotary abrading wheel, a support therefor comprising means for angular adjustment of the plane of said rotary abrading wheel with relation to the plane of the grinding wheel, braking means for said abrading wheel, and quick release 15 means for said braking means.

5. In mechanism for truing and dressing 10 grinding wheels, the combination of a normally quiescent rotary abrading part, a mandrel therefor, opposed bearings for said 15 mandrel, and resilient means operatively disposed between said bearings for causing resilient axial take-up movement between said bearings.

6. In mechanism for truing and dressing 15 grinding wheels, the combination of a nor-

mally quiescent rotary abrading part, a mandrel therefor, opposed bearings for said mandrel, resilient means operatively disposed between said bearings for causing resilient axial take-up movement between said 70 bearings, and braking means for said mandrel.

7. In mechanism for truing and dressing 75 grinding wheels, the combination of a normally quiescent rotary abrading part, a mandrel therefor, opposed bearings for said mandrel, resilient means operatively disposed between said bearings for causing resilient axial take-up movement between said 80 bearings, braking means for said mandrel, and means for adjusting said braking means.

8. In mechanism for truing and dressing 85 grinding wheels, the combination of a normally quiescent rotary abrading part, a mandrel therefor, opposed bearings for said mandrel, resilient means operatively disposed between said bearings for causing resilient axial take-up movement between 90 said bearings, braking means for said mandrel, and quick release means for said braking means.

9. In mechanism for truing and dressing 95 grinding wheels, the combination of a normally quiescent rotary abrading part, a mandrel therefor, opposed ball-bearings for said mandrel respectively comprising opposed races, means for positioning one of the races of one of said ball-bearings, a part 100 movable axially with relation to the mandrel, means for securing a race of the other of said ball-bearings to said part, and spring means operatively disposed between said part and said mandrel arranged for axial 105 take-up movement in said ball-bearings.

10. In mechanism for truing and dressing 110 grinding wheels, the combination of a normally quiescent rotary abrading part, a mandrel therefor, spaced-apart bearings for said mandrel, an annular braking part on 115 said mandrel between said bearings, and a coacting braking part for said annular braking part.

11. In mechanism for truing and dressing 115 grinding wheels, the combination of a normally quiescent rotary abrading part, a mandrel therefor, a spaced-apart bearings for said mandrel, an annular braking part on said mandrel between said bearings, a coacting braking part for said annular braking part, and resilient means for said coacting braking part to urge braking friction on said first-named braking part.

12. In mechanism for truing and dressing 125 grinding wheels, the combination of a normally quiescent rotary abrading part, a mandrel therefor, spaced-apart bearings for said mandrel, an annular braking part on said mandrel between said bearings, a coacting braking part for said annular brak-

- ing part, resilient means for said coacting braking part to urge braking friction on said first-named braking part, and means for adjusting said resilient means.
- 5 13. In mechanism for truing and dressing grinding wheels, the combination of a normally quiescent rotary abrading part, a mandrel therefor, spaced-apart bearings for said mandrel, an annular braking part on said 7 mandrel between said bearings, a coacting braking part for said annular braking part, resilient means for said coacting braking part to urge braking friction on said first-named braking part, and quick release 10 means for said coacting braking part.
14. In mechanism for truing and dressing grinding wheels, the combination of a normally quiescent rotary abrading part, a mandrel therefor, a pair of ball-bearings 13 for said mandrel, an annular braking part on said mandrel, means for holding the inner race of one of said ball-bearings to said mandrel, a sleeve axially movable on said mandrel, means for holding the inner race 16 of the other of said ball-bearings to said sleeve, a spring operatively disposed between said sleeve and said mandrel, and positioning means for the outer races of said ball-bearings.
- 20 15. In mechanism for truing and dressing grinding wheels, the combination of a normally quiescent rotary abrading part, a mandrel therefor, a bearing-housing, ball-bearings in said housing for said mandrel, 23 spring means in said housing urging axial take-up movement in said ball-bearings, and braking means in said housing for said mandrel.
- 25 16. In mechanism for truing and dressing 26 grinding wheels, the combination of a normally quiescent rotary abrading part, a mandrel therefor, a bearing-housing, ball-bearings in said housing for said mandrel, spring means in said housing urging axial 29 take-up movement in said ball-bearings, braking means in said housing for said mandrel, a shank for said housing, and brake control means supported by said shank.
- 30 17. In mechanism for truing and dressing 33 grinding wheels, the combination of a normally quiescent rotary abrading part, a mandrel therefor, a bearing-housing for said mandrel, a pair of ball-bearings for said 36 mandrel in said housing, a tube separating the outer races of said ball-bearings, means for securing said outer races in said housing, a sleeve about said mandrel, means for securing the inner races of said ball-bearings 40 respectively to said mandrel and to said sleeve, and a spring causing axial take-up movement between said mandrel and said sleeve.
- 35 18. In mechanism for truing and dressing 44 grinding wheels, the combination of a nor- mally quiescent rotary abrading part, a mandrel therefor, a bearing-housing for said mandrel, a shank extending from the latter, a pair of ball-bearings for said mandrel in said housing, separating means in said housing for the outer races of said ball-bearings, means for securing said outer races in said housing, a sleeve about said mandrel, means for securing the inner races of said ball-bearings 48 respectively to said mandrel and to said sleeve, a spring causing axial take-up movement between said mandrel and said sleeve, an annular brake-member on said mandrel in said tube, a brake-shoe for said brake-member, and a stem in said shank for said brake-shoe.
- 50 19. In mechanism for truing and dressing 52 grinding wheels, the combination of a normally quiescent rotary abrading part, a mandrel therefor, a bearing-housing for said mandrel, a shank extending from the latter, a pair of ball-bearings for said mandrel in said housing, separating means in said housing for the outer races of said ball-bearings, means for securing said outer races in said housing, a sleeve about said mandrel, means for securing the inner races of said ball-bearings 56 respectively to said mandrel and to said sleeve, a spring about said mandrel causing axial take-up movement between said mandrel and said sleeve, an annular brake-member on said mandrel in said tube, a brake-shoe for said brake-member, and a stem in said shank for said brake-shoe.
- 55 20. In mechanism for truing and dressing 60 grinding wheels, the combination of a normally quiescent rotary abrading part, a mandrel therefor, a bearing-housing for said mandrel, a shank extending from the latter, a pair of ball-bearings for said mandrel in said housing, separating means in said housing for the outer races of said ball-bearings, means for securing said outer races in said housing, a sleeve about said mandrel, means for securing the inner races of said ball-bearings 64 respectively to said mandrel and to said sleeve, a spring about said mandrel causing axial take-up movement between said mandrel and said sleeve, an annular brake-member on said mandrel in said tube, a brake-shoe for said brake-member, a stem in said shank for said brake-shoe, a spring for said stem, and means between said shank and said spring for adjusting said spring.
- 65 21. In mechanism for truing and dressing 68 grinding wheels, the combination of a normally quiescent rotary abrading part, a mandrel therefor, a bearing-housing for said mandrel, a shank extending from the latter, a pair of ball-bearings for said mandrel in said housing, separating means in said housing for the outer races of said ball-bearings, means for securing said outer races in said housing, a sleeve about said mandrel, means for securing the inner races of said ball-bearings 72 respectively to said mandrel and to said sleeve, a spring about said mandrel causing axial take-up movement between said mandrel and said sleeve.
- 75 22. In mechanism for truing and dressing 78 grinding wheels, the combination of a nor- mally quiescent rotary abrading part, a mandrel therefor, a bearing-housing for said mandrel, a shank extending from the latter, a pair of ball-bearings for said mandrel in said housing, separating means in said housing for the outer races of said ball-bearings, means for securing said outer races in said housing, a sleeve about said mandrel, means for securing the inner races of said ball-bearings 82 respectively to said mandrel and to said sleeve, a spring about said mandrel causing axial take-up movement between said mandrel and said sleeve.
- 80 23. In mechanism for truing and dressing 84 grinding wheels, the combination of a nor- mally quiescent rotary abrading part, a mandrel therefor, a bearing-housing for said mandrel, a shank extending from the latter, a pair of ball-bearings for said mandrel in said housing, separating means in said housing for the outer races of said ball-bearings, means for securing said outer races in said housing, a sleeve about said mandrel, means for securing the inner races of said ball-bearings 88 respectively to said mandrel and to said sleeve, a spring about said mandrel causing axial take-up movement between said mandrel and said sleeve.
- 85 24. In mechanism for truing and dressing 90 grinding wheels, the combination of a nor- mally quiescent rotary abrading part, a mandrel therefor, a bearing-housing for said mandrel, a shank extending from the latter, a pair of ball-bearings for said mandrel in said housing, separating means in said housing for the outer races of said ball-bearings, means for securing said outer races in said housing, a sleeve about said mandrel, means for securing the inner races of said ball-bearings 94 respectively to said mandrel and to said sleeve, a spring about said mandrel causing axial take-up movement between said mandrel and said sleeve.
- 90 25. In mechanism for truing and dressing 96 grinding wheels, the combination of a nor- mally quiescent rotary abrading part, a mandrel therefor, a bearing-housing for said mandrel, a shank extending from the latter, a pair of ball-bearings for said mandrel in said housing, separating means in said housing for the outer races of said ball-bearings, means for securing said outer races in said housing, a sleeve about said mandrel, means for securing the inner races of said ball-bearings 100 respectively to said mandrel and to said sleeve, a spring about said mandrel causing axial take-up movement between said mandrel and said sleeve.

causing axial take-up movement between said mandrel and said sleeve, an annular brake-member on said mandrel in said tube, a brake-shoe for said brake-member, a stem in said shank for said brake-shoe, and quick release means on said stem for said brake-shoe.

In testimony whereof, I have hereunto signed my name in the presence of two subscribing witnesses.

JAMES F. MIRRIELEES.

Witnesses:

EDWARD J. BRIGGS,
DELMA WERNING.
